UNITED STATES PATENT OFFICE

1,985,109

SIFTING APPARATUS

Frederick George Schwartz, Bexley, Ohio

Application February 11, 1933, Serial No. 656,350

4 Claims. (Cl. 209—337)

This invention relates to a sifting apparatus, and it is an object of the invention to provide an apparatus of this kind wherein a sifting element when desired may be readily removed so that the device may be employed for the collection of rubbish.

Another object of the invention is to provide a device of this kind including two separate units, one of the units constituting a housing and the other a sifting element adapted to be reciprocated upon the housing and wherein the housing carries means for suspending a bag or kindred collecting receptacle within the housing.

The invention consists in the details of construction and in the combination and arrangement of the several parts of my improved sifting apparatus whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a vertical sectional view taken through a sifting apparatus constructed in accordance with an embodiment of my invention;

Figure 2 is an enlarged fragmentary sectional view taken substantially on the line 2—2 of Figure 1 looking in the direction of the arrows;

Figure 3 is a fragmentary detail view partly in section and partly in elevation illustrating the mounting for one of the supporting rollers carried by the housing unit and with which the sifting element engages.

As herein disclosed my improved apparatus comprises two units A and B, the unit A constituting a sifting element and the unit B a housing of desired dimensions.

The element or housing B comprises in its construction the corner posts 1 each preferably an angle iron with said posts connected by the panels 2 of sheet metal or any other desired material. The panels 2 as illustrated in Figure 1 of the drawing preferably terminate a slight distance above the lower ends of the corner posts or irons 1 so that such panels will offer no obstruction to the desired placement of the unit or housing B. The lower ends of the corner posts or irons 1 are also preferably pointed, as at 3, to facilitate the maintenance of the apparatus against shifting or creeping during a sifting operation.

Opposed panels 2 slightly below their upper ends have secured thereto the transversely directed angle members or irons 4, a flange 5 of each of which being inwardly disposed.

Welded or otherwise secured to the under surface of the flanges 5 of the members 4 are the outstanding marginal portions 6 of a hopper 7. This hopper 7 has its side walls inwardly and downwardly inclined and opposed walls of said hopper adjacent the lower margins thereof have suitably secured exteriorly thereof the flanges 8 with which are operatively engaged the flanges 9 extending outwardly from a neck member 10. Interposed between the flanges 8 and 9 are the strips 11, said strips being of a width whereby is provided opposed runways 12 for a slide valve 14. This valve 14 serves of course to provide means to effectively close the flow down through the hopper 7. The neck member 10 is provided with the external hook members 15 the bills of which being preferably upwardly disposed, said hook members 15 providing a means whereby a bag or kindred container C may be readily suspended from said neck member 10 to collect the material passing down through the member 10 from the hopper 7.

Each of the flanges 5 and the portion 6 of the hopper 7 at desired points therealong have disposed therethrough openings 16 in each of which is positioned a roller 17. This roller 17 extends a slight distance above the flange 5 and is provided at its opposite ends with the trunnions 18 which are rotatably received between the flange 5 and the portion 6 of the hopper 7 in the registering bearing recesses 19. The rollers 17 have directly resting thereon from above the elongated side irons or members 20 secured to the lower portions of the upstanding hopper 21 comprised in the sifting element A.

The irons or members 20 extend a desired distance beyond opposite sides of the hopper 21 and the outer or free ends of the irons or members 20 are connected by the cross handles 22 providing effective means to reciprocate the unit A to effect a separation of the material placed within the hopper 21, said separation of course being effected by the screen fabric 23 disposed over the bottom of the hopper 21.

The opposite walls of the hopper 21 are continued by the outstanding plates 24 terminating in the depending flanges 25, said flanges 25 providing stops for contact with the upper end of the unit B to limit the extent of reciprocation of the unit A when in working position upon the unit B. As is believed to be apparent the

spacing of the flanges 25 with respect to the hopper 21 determines the maximum extent of endwise travel of the hopper 21. The plates 24 also serve to maintain substantially closed the 5 upper portion of the hopper 7 irrespective of the position of the sifting element A to hold back the dust during a sifting operation.

The upper or top end of the hopper 21 is adapted to be closed in a conventional manner 10 by a removable cover or lid 26.

With my improved apparatus it is to be noted that ashes may be readily sifted when desired with the resultant saving of the cinders the 15 ashes of course being collected within the bag or kindred container C. The bag C when filled can be readily removed and replaced.

When desired the unit A can be entirely separated from the unit B thus providing a structure whereby the bag or container C may be 20 employed for the collection of rubbish.

From the foregoing description it is thought to be obvious that a sifting apparatus constructed in accordance with my invention is particularly well adapted for use by reason of the convenience and facility with which it may be assembled and operated, and it will also be obvious 25 that my invention is susceptible of some change and modification without departing from the principles and spirit thereof and for this reason 30 I do not wish to be understood as limiting myself to the precise arrangement and formation of the several parts herein shown in carrying out my invention in practice except as hereinafter claimed.

35 I claim:—

1. An apparatus of the class described comprising two separable units, one of said units constituting a housing and the other a sifting element, a hopper disposed over the upper portion 40 of the housing, rollers carried by the marginal portions of the hopper, the sifting element when applied resting upon the rollers, and plates carried by the sifting element and extending fore and aft thereof, said plates having depending 45 flanges providing stops for contact with the housing for limiting the extent of reciprocation of the

sifting element, said plates being of a length to close the upper portion of the hopper fore and aft of the sifting element irrespective of the position of the sifting element.

2. An apparatus of the class described comprising two units, one of said units constituting a housing and the other a sifting element, a hopper disposed over the upper portion of the housing, means for supporting the sifting element by the housing above the hopper, said sifting element having reciprocating movement, plates extending fore and aft of the sifting element and of a length to substantially close the upper portion of the hopper fore and aft of the sifting element in the different positions of the sifting element, and means carried by said plates for contact with the housing to limit the extent of reciprocation of the sifting element. 5

3. An apparatus of the class described comprising a supporting structure, a hopper carried thereby for discharge within a container, a sifting element mounted on the supporting structure for reciprocating movement above the hopper, plates carried by the sifting element and extending fore and aft thereof, said plates being 20 of a length to substantially close the upper portion of the hopper in all positions of the sifting element during its reciprocation, said plates having means contacting with the supporting structure 25 for limiting the extent of reciprocation of the sifting element. 30

4. An apparatus of the class described comprising a supporting structure, a hopper carried thereby for discharge within a container, a sifting element mounted on the supporting structure for reciprocating movement above the hopper, plates carried by the sifting element and extending fore and aft thereof, said plates being of a length to substantially close the upper portion of the hopper in all positions of the sifting element during 40 its reciprocation, said plates having means contacting with the supporting structure for limiting the extent of reciprocation of the sifting element, and means for closing the hopper against flow therethrough. 45
